ANTIFOULING SINKER

Virgil L. Bowman, Buhl, Idaho

Application September 18, 1950, Serial No. 185,397

6 Claims. (Cl. 43—43.12)

1

The present invention relates to new and useful improvements in sinkers and more particularly to an anti-fouling sinker.

An important object of the invention is to provide a connector for an elongated sinker and to which the sinker is pivoted between its ends to provide an endwise swinging or tumbling movement for the sinker to free itself from fouling with submerged objects.

Another object is to provide resilient skids at the front end of the connector to ride over submerged objects.

A further object is to provide a wire frame or harness forming the connector and including side bars having trunnions at their rear ends to which the sinker is pivoted and providing an adjustable line attaching member connected to the bars and holding the trunnions engaged with the sinker.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a central longitudinal sectional view;

Figure 3 is a side elevational view showing the anti-fouling action of the sinker; and

Figures 4 and 5 are transverse sectional views taken on the lines 4—4 and 5—5 of Figure 1.

Referring now to the drawing in detail, wherein for the purpose of illustration I have disclosed a preferred embodiment of my invention, the numeral 5 designates the wire connector frame or harness and which is shaped to provide a pair of side bars 6 united at their front ends by upwardly and rearwardly curved loops or skids 7 and which are united with each other by a cross bar 8 at the rear portion of the loops.

The rear ends of side bars 6 are formed with opposed trunnions 9 received in an opening 10 in the opposite sides of an ovate sinker 11 and nearer one end of the sinker to provide a weighted rear end 12, and between the loops or skids 7 and trunnions 9 the bars 6 are undulated to form notches 15.

A line attaching cross bar 13 is formed at its ends with eyes 14 slidably mounted on the side

2

bars 6 and selectively held in notches 15 in the side bars to adjust the cross bar forwardly or rearwardly thereon. A sleeve 16 is placed on cross bar 13 with a circumferential groove 17 therein to center a line 18 attached thereto on the cross bar. The line extends from the sleeve 16 forwardly through a wire guide 19 attached between the rear portion of loops 7.

The elongated sinker 11 is free to swing on the trunnions 9 at the rear ends of side bars 6 to prevent fouling with a submerged object 20 when the sinker is pulled upwardly by the line. The resilient wire loops or skids 7 at the front ends of the connector frame or harness 5 will also more easily ride over the jagged surface of the object and should the loops or skid become fouled, the resiliency thereof will cause the same to flex when the line is pulled and suddenly released to free itself.

An eye 21 is secured in one end of the sinker for attaching directly to a fish line, when the frame or harness 5 is not used, and an opening 22 is formed in the other end of the sinker for attaching fish hooks (not shown) thereto.

In the operation of the device, the trunnions 9 at the rear ends of side bars 6 are inserted in opening 10 to position the sinker between the bars for free rocking or rotary movement. Line attaching cross bar 13 is adjusted either forwardly or rearwardly on bars 6 in the notches 15 depending on the pulling force the bars 6 and trunnions 9 are desired to withstand before the arms flex sufficiently to release the trunnions without breaking the line, should the sinker become hopelessly fouled.

Should the sinker encounter a submerged object, skids or loops 7 will tend to ride over the object and the lighter front end of the sinker, upon striking the object, will tumble or turn over about the axis of the trunnions 9 to prevent fouling of the sinker.

Having described the invention, what is claimed as new is:

1. A fishing sinker comprising a line connector including a line attaching cross-bar, a line guide carried by the connector forwardly of the cross-bar, and an elongated solid body pivotally mounted to the rear end of the connector for endwise swinging movement of the body.

2. A fishing sinker comprising a line connector including a pair of spaced apart parallel rods, a pair of opposed trunnions at the rear ends of the rods, a cross-bar connected to the parallel rods substantially midway between the ends of the rods and adapted for attaching a line there-

to, and an elongated solid body pivotally mounted on the trunnions for endwise swinging movement of the body.

3. A fishing sinker comprising a line connector including a pair of parallel bars, a rearwardly curved skid at the front end of each bar, a connecting bar uniting the outer end portion of the skids with each other, and an elongated solid body pivoted to the rear ends of the bars for endwise swinging movement of the body.

4. A fishing sinker comprising a resilient wire frame including a pair of parallel bars united with each other at one end, an elongated solid body pivoted at its sides to the free ends of the bars for rotary movement of the body, line attaching means connected to the bars forwardly of the body and holding the bars engaged with the body, and a line guide adjacent the united ends of the bars forwardly of said line-attaching means.

5. A fishing sinker comprising a wire frame including a pair of parallel bars having resilient parallel loops formed at the front ends thereof and a third bar connecting the outer end portions of the loops to each other, opposed trunnions at the rear ends of the parallel bars, an ovate body pivoted at its sides to the trunnions for rotary movement of the body, a cross bar adjustable longitudinally on the parallel bars and holding the latter rigid and adapted for attach-

ing a line thereto, and a line guide supported between the loops forwardly of the cross bar.

6. A fishing sinker comprising a wire frame including a pair of spaced apart parallel bars united with each other at their front ends, opposed trunnions formed at the rear ends of the bars, a non-buoyant body having openings at its opposite sides for rockably mounting said body on the trunnions between the bars, said bars being undulated to form notches therein, and a cross bar adapted for attaching a fishing line thereto and having its ends selectively engaged in said notches to permit adjustment of the cross bar forwardly or rearwardly on said parallel bars to vary the pull on the line necessary to cause release of the trunnions from said openings when the body becomes fouled.
